OXYGEN MASK

Allan M. Russell, Shaker Heights, Ohio

Application August 7, 1952, Serial No. 303,030

15 Claims. (Cl. 128—205)

This invention pertains to oxygen masks, and more particularly to an improved oxygen mask of the continuous flow type, and is a continuation in part of my copending application, Ser. No. 222,086, filed April 21, 1951 and now abandoned.

Masks to cover the mouth and nose for supplying oxygen to the wearer, have been well known for some time. Such masks are used primarily by aviators who will fly at altitudes where the atmosphere is of a density which will not support human life, or at least where the senses are dulled. If additional oxygen can be supplied at these altitudes, a full or nearly full efficiency may be maintained.

Various types of masks adapted to cover the nose alone, or the nose and mouth, to supply oxygen to an aviator have been used. In general, at first these masks were primarily concerned with the mechanical process of bringing oxygen to the breathing passages and removing the exhaled gases, the comfort of the wearer being a secondary consideration. Later, some refinements were made with the comfort factor of the user in mind. However, present masks are still heavy, cumbersome devices and frequently produce chafing where the edges of the mask contact the face. These disadvantages resulted largely because of the use of molded rubber in their construction. Such rubber is cured by the heat of the mold and is therefore hardened somewhat. It is also inherent in molded rubber articles for the rubber to be of not less than a certain thickness which results in a mask that is actually heavier than is necessary. The end result was that the prior masks were so uncomfortable that they distracted the attention of the wearer at a time when his full attention was needed elsewhere, and frequently resulted in their removal at times when they should not have been removed.

By my invention, I provide a mask fully if not more efficient than prior devices, yet more comfortable because of its lighter weight and softer material. The mask is also less expensive to manufacture. Because of its construction, it is considerably easier to store and/or carry. The cheapness of manufacture is such that the masks may be disposable, if desired. These advantages are gained by the formation of the mask made by, but not restricted in its fabrication to, a dipping process from a material, such as latex rubber, that preferably does not change its flexibility with changes in the temperature. Rigidity is obtained by the placement of certain valves, and adjustability to various facial characteristics, by use of malleable bridges across the nasal and chin section. Because of the construction and the placement of the valves, it is even possible for persons wearing the masks to carry on a limited conversation without removal thereof. The more highly flexible parts, particularly the integral thinner inner flap part, are so constructed that the actual use thereof causes the parts to conform to certain facial irregularities, thus making the mask universal and a more perfect fit for divers persons.

Of particular interest is the fact that the placement of

2

the valves and the reinforcements enable a much thinner, softer, and more flexible material to be used, which enables the material to cling to and conform to the facial contours, providing a good comfortable seal and still allow certain parts, particularly around the nostrils and mouth, to be held away and provide least interference with their normal functions.

Although the use described has been in the field of aviation, another, and one of the principal uses, will be that of oxygen therapy. Obviously, such uses may be in hospitals and private institutions, as well as aviation, where it can be used to administer mixtures of gases other than pure oxygen.

15 A more complete understanding of my invention may be acquired by reference to the following description and figures which form a part of this application.

In the drawings:

Fig. 1 is a front elevational view of the mask;

Fig. 2 is a sectional view along line 2—2 of Fig. 1;

Fig. 3 is a sectional view along line 3—3 of Fig. 1;

Fig. 4 is a rear elevational view of the mask;

Fig. 5 is a view partly in section showing an alternative form of mask;

Fig. 6 is a section on the line 6—6 of Fig. 4;

20 Fig. 7 is a view similar to Fig. 1 of a modified form thereof;

Figs. 8, 9 and 10 are views of the mask of Fig. 7 corresponding to the views of Figs. 2, 3 and 4.

Briefly, my invention comprises a unitary oxygen mask 30 and re-breathing bag formed preferably of latex rubber by a dipping process. The mask is very soft and flexible, particularly the inner face-engaging part, but is stiffened at the cheeks by provision of inhalation and exhalation valves of a common construction in the proper location and is molded to the bridge of any user's nose and chin by the provision of malleable wire bridge members which may be easily bent by the wearer to fit any wearer. Wide marginal convex flanges enable a seal to be formed against the user's face and may be trimmed to allow sufficient opening for the mouth and nose and avoid interference therewith.

More particularly, and referring to the figures, the mask is composed of two principal parts; the face piece 45 10 and the reservoir re-breathing bag 11. These two parts are preferably formed integrally together and are joined by a flexible neck which is arched so as to position the bag away from the wearer's clothing and still permit free bending movement of the bag relative to the face piece. The bag 11 is preferably of the fluted type and is provided with a tube 13 for connection to the oxygen supply system. This tube extends into the bag sufficiently far to avoid stopping up of the end by the sides of the bag. Holes 14 in the tube 13 also assure an outlet of the tube 50 into the bag. It will be apparent to those skilled in the art that the bag could be made detachable if desired.

The face piece 10 is formed to provide an open sided chamber to receive the nose and mouth of the wearer. Across the upper or nasal section, a framework 55 of malleable wire is provided. This frame or bridge is preferably a continuous loop of roughly triangular shape and surrounds the portion of the mask which would ordinarily cover the wearer's nose. The frame 15 is completely embedded within the material of the mask, and the wearer is therefore free from any contact with the metal. By making the frame of a continuous loop, no free ends are provided which might wear or puncture the rubber or material of which the mask is made.

Immediately below the frame 15 on both sides, a pair of 60 turrets 16 is provided, in each of which is disposed a standard type rubber check valve 17. One of these is arranged for inhalation, and the other for exhalation, as

appears in Fig. 3. These valves are relatively thick and are located in their illustrated positions for the purpose of adding stiffness to the face piece which is otherwise very soft and flexible. It is envisioned, however, Fig. 5, that only an exhalation valve could be used in which case all inhaled air would come through the bag 11. This exhalation valve could be located in the center immediately above the neck 12 or preferably could be provided by using two valves as in the illustrated embodiment and simply turning both of them with the diaphragm portion 20 outwardly. This valve could also be a combination of exhalation and inhalation valve of which there are many known types.

The neck 12 is also formed with a section 21 of diminished size to receive a removable check valve, not shown, arranged to prevent exhaled gases from mixing with the oxygen in the bag 11 when desirable. The valve is of such a resiliency that the oxygen is inhaled first and the outside air secondarily to provide the proper physiological balance.

At the rear of the face piece 10 is formed a wide, thin, flexible flange 22 (Figs. 2, 3 and 4) which extends from the periphery of the face piece inwardly, and in transverse section, is generally convex toward the face. This flange is cut to define an opening with which the oral and nasal portions of the face may fit, the upper portion at the top 23 accommodating the wearer's nose. The flange is otherwise unbroken. Because of this construction, the flange 22 is effective to seal the mask to the face without cutting off the circulation and because of the manner of its use, the actual breathing causes the pressure on the face of the wearer to alternate between two extremes, further increasing the comfort and eliminating possibility of the structure interfering with the circulation of blood in the face. This is true because of the soft flexible material of which the mask is formed. Moreover, when the mask is moved on the face, the flange has a tendency to be deformed or to roll on the face rather than to slide as was the case with previous masks molded of rubber. Thus there is considerably less likelihood of chafing with my new mask, both because of the material and the structure.

As can best be seen in Fig. 6, the flange is formed so that it bulges slightly toward the wearer's nose at 40 which enables the flange to conform more readily to the wearer's nose, since these portions contact and fit into the hollow portions in each side of the bridge of the wearer's nose preventing leakage around these portions particularly in the area near the eyes. This flange may be trimmed where desirable to avoid interference with the wearer's nose and mouth.

It will be apparent that, because of this structure, one mask can be made that will conform to various facial contours without causing discomfort.

The mask is held on the wearer's head by a pair of soft, resilient latex rubber straps 25 having a series of holes 26 adapted to be disposed over attaching buttons 27 provided at the edges of the face piece. These buttons may be made from metal or other hard material as a form, completely covered in the dipping process by the material of the mask. Use of the series of holes along with the easily stretched material of the straps 25 allows adjustment of the device to almost any shape or size of head. The arrangement of the buttons may be varied and the number decreased or increased as desired.

Although the straps (Fig. 1) are shown as being secured to the buttons through the end hole of the straps, a preferred method of securing the straps on the button consists of placing the strap on the buttons by forcing one of the holes intermediate the ends over the buttons and then folding the strap so that one of the other holes, preferably the next adjacent hole, toward the strap is opposite to and can be forced over the button to provide a double thickness of strap material, around the button, which results in a loop on the free side of the strap, with the tag end extending back beyond the face of the mask

where it does not interfere with the wearer's vision. The portion placed on the button last acts as a washer helping to prevent displacement of the strap from the button when it is stretched. Because of the above described construction, I am able to use a very flexible head strap without fabric which also adds to the comfort of the wearer and effectiveness of the fit.

As stated, the mask is preferably formed by a dipping process. That is, a mandrel of the proper shape is dipped 10 the required number of times into liquid latex, each time adding a layer to the thickness of the parts dipped. The inserts being applied between dippings enable them to be properly placed and wholly covered. Parts may be selectively dipped to provide different thicknesses. For 15 example, the main body of the bag 11 is somewhat thinner than the face piece 10. The entire mask, however, is very soft and pliable because of the use of a dipped material rather than molded rubber. It is conceived, however, that soft pliable materials other than latex rubber might be used. Among such materials might be included various 20 well-known flexible materials. Another material which might be used under certain conditions where the mask may be discarded, might be certain types of paper. These softer materials may be used in the mask principally because of the simplified form which is nonetheless sufficiently rigid to keep its form when in use, and also because of the malleable frame which allows the wearer to 25 adjust the nasal section to his own face.

An alternative form of mask is illustrated in Fig. 5. 30 This mask utilizes the same form of bag 11, having a neck 12 with a reduced section 21 for the insertion of a check valve if desired. The face piece 10' is also similar in that the wide flange 22 which presses against the wearer's face connects to the face piece in a smooth curved edge which 35 will roll on the wearer's face. A frame 15 is also provided in the nasal section so that the mask may be fitted to the individual face. Instead of two valves, however, one for inhaling and one for exhaling, only a single valve 30 is provided in this embodiment. This may be any of 40 a well known type of valve, the one illustrated having an inner wall diaphragm 31 and an outer diaphragm 32 somewhat larger and perforated. Both of these diaphragms are of soft rubber or the like. On inhaling, the air presses through the perforations 33 of the outer diaphragm and 45 opens it while the outer diaphragm is held against a seat in the outer housing 34 of the valve. On exhaling, the larger outer diaphragm 32 is raised off its seat allowing the air to flow around the outer edges thereof.

This single valve, while providing somewhat less stiffening than the two valves of the prior described embodiment, still provides enough rigidity to keep the mask operating and comfortable. In this, it is particularly assisted by the frame 15 because of its closer proximity thereto, as will be noted in Fig. 5.

55 Referring to Fig. 7 et seq., it will be noted that there are several departures from the construction shown in Figs. 1 to 6, although the general advantages due to the construction are still retained. In this embodiment, as can be seen by the drawings, the strap buttons 27' are positioned opposite the points of the wire members, so that the pull by the straps is distributed evenly over the upper zone by the malleable wire. This has an important effect, in that the mask may be secured more tightly and made of much lighter weight materials without any tendency 60 toward distortion, particularly at the margin, due to the pull by the strap.

In this embodiment, I preferably use two of the bendable malleable wire reinforcements. The one in the upper zone which may be shaped to conform to different nose contours, as previously described, and another member in the chin zone which may also be shaped to conform to different chin shapes by the wearer.

In this case, the lower wire 50 is provided being built 70 into the structure as previously described and comprises a continuous loop, the lower side 51 of which follows the

curved contour of the margin closely spaced from the edges and continuous around the margin to a point 52 spaced below and to one side of the inlet and outlet valves and then curves back at 53 substantially parallel to but spaced from the lower section below the neck 12. The attaching buttons 27" are disposed opposite and close to the ends of the loops so that the strains of the straps are transmitted from the buttons to the loop and distributed in the area opposite the chin.

The buttons 27' and 27" are thus more widely separated than in the other embodiments. This enables a more even distribution of the forces exerted by the straps for holding the same in position.

In addition to the wider distribution and hence better holding, it will be noted that the stresses are exerted in two spaced apart zones, one over the nose and the other over the chin, which is facilitated by the placement of the buttons close to the extremities of the malleable inserts and which inserts assist in the distribution thereof. This in itself has a better sealing effect and still another advantage is realized in that less of the forces are applied to the area intermediate the two zones. The placing of the inserts in the two separate zones effectively provides a hinging action which, during use enables a more or less independent movement of the upper and lower zones. In other words, the lower zone is freer to move without restraint from the upper zones and thus allows more freedom of the jaw and lip movements when talking. Due to this freedom of movement and the greater ability of the wearer to work his lower jaw, it lessens the strain when the mask is worn over longer periods of time.

Still another advantage resides in the fact that the term "hinging action" enables the mask to be folded into a much smaller packet. That is, the upper section may be folded down and the lower section folded up and the rebreather bag wrapped around the two to make a small compact package which may be readily carried in the pocket of the user or stored.

In this embodiment, means is provided to deflect the outlet gases away from the wearer's eyes, thus preventing steaming of his glasses and preventing disconcerting drafts into the eyes. This is effected by providing an integral shield 60 of half moon shape which extends from the upper periphery of the valve engaging flange 16 substantially diametrically across but spaced away from the valve. Exhaust air is deflected thereby in a downward direction.

In this instance, provision is made for the installation of a microphone, and comprises a pocket 65 formed in the face between the valves. The pocket also opens into the neck 12 opposite to the mouth of the wearer in order that the sensitive element 66 of the microphone may have ample clearance with the surrounding parts and be in a direct line with the voice. A tube 67 extends from the forward part of the packet for the microphone conductors 68.

As can best be seen in Fig. 10, the face engaging flange 22 is substantially the same as is the preceding embodiment except that in place of the nose slot 23, the material is provided with an indentation 63 which may engage the upper part of the bridge of the nose. It also may be cut out as shown in Fig. 4 if desirable, but with the construction shown, there is less chance of the material being torn during installation or use.

By the structure of the foregoing invention, I am able to construct a simpler unbreakable mask having a minimum of components which may be worn for long periods of time with a minimum of discomfort to the wearer and wherein a greater freedom of movement is possible without chafing the face of the wearer. The mask, because of the malleable reinforcements, may be bent to provide a better seal with the wearer's face and is thus adaptable to various persons having widely different facial contours. The reinforcements together with the placement of the strap receiving buttons distribute the stresses over widely

spaced but independent zones, allowing a certain freedom of movement between the upper and lower parts as well as permitting the same to be folded into a very small compact package. It is also contemplated that the mask be made of a material that may be readily sterilized when desired, and because of the bag being integral with the face, the weaknesses inherent in this prior art are overcome because the neck of the bag does not need to be stretched over connecting tubes with resultant cracking or tearing that frequently occurs in time.

Having thus described my invention, I am aware that numerous and extensive departures may be made therefrom without departing from the spirit or scope of my invention as defined in the appended claims.

I claim:

1. A mask for the administration of a gas having a face piece formed of soft, pliable material, said face piece having a nasal section and an oral section, a malleable wire frame embedded in said material at said nasal section to stiffen said face piece, said frame being a wire-like substantially triangular loop of material disposed in the upper part of the mask having one portion following the upper contour of the mask near the edge and the lower portion extending across the mask, said portions of the loop being bendable in different zones to conform to facial configurations of the wearer, said face piece being formed to provide a turret opening on each side of said oral section, check valves disposed in said openings to allow inhalation and exhalation, said valves thereby stiffening said oral section, and inlet means at said oral section to provide for the ingress of gas into said face piece.
2. A mask for the administration of a gas having a face piece formed of soft, pliable material, said face piece having a nasal section and an oral section, a malleable wire frame embedded in said material at said nasal section to stiffen said face piece, said frame being a wire-like loop of material disposed in the upper part of the mask having one portion following the upper contour of the mask near the edge, and the lower portion extending across the mask, said portions being bendable in different zones to conform to facial configurations of the wearer, and inlet means at said oral section to provide for the ingress of gas into said face piece.
3. A mask for the administration of a gas having a face piece formed of soft, pliable material, said face piece having a nasal section and an oral section, a malleable wire frame embedded in said material at said nasal section to stiffen said face piece, said frame being of triangular formation and disposed in the upper part of the mask having one portion following the upper contour of the mask near the edge, and the lower portion extending across the mask, said portions being bendable in different zones to conform to facial configurations of the wearer, and to fit the wearer's nose, said face piece being formed to provide a turret opening on each side of said oral section, check valves disposed in said openings to allow inhalation and exhalation of air, said valves thereby stiffening said oral section, and inlet means at said oral section to provide for the ingress of gas into said face piece.
4. A mask for the administration of a gas comprising a face portion formed of soft, pliable material and providing an upper nasal section and a lower oral section, a malleable wire frame embedded in the material of said nasal section and being of a material which may be bent to fit the contour of a wearer's nose and reinforcing the mask in said nasal section, a second malleable wire frame embedded in the material of said mask in the oral section and bendable to fit the contour of a wearer's chin and reinforcing the chin section, the mask intermediate said sections being flexible to permit independent movement of said sections.
5. A mask for the administration of a gas comprising a face portion formed to provide a chamber the walls of which are of soft, pliable material, said chamber providing an upper nasal section and a lower oral section, a

malleable wire frame embedded in the material of said nasal section and being of a material which may be bent to fit the contour of a wearer's nose and reinforcing the mask in said nasal section and comprising a wire-like endless loop having one portion following the upper contour near the edge and a lower part joining the upper part to form apexes therewith adjacent the extremities of the upper part past and extending across the mask, a second malleable wire frame embedded in the material of said mask in the oral section and bendable to fit the contour of a wearer's chin and reinforcing the chin section and comprising a wire-like endless loop having one portion following the lower contour near the edge and an upper part forming apexes with said lower part at the ends of the upper part and extended across the mask, the mask intermediate said sections being flexible to permit independent movement of said sections.

6. A mask for the administration of a gas comprising a face portion formed to provide a chamber the walls of which are of soft, pliable material, said chamber providing an upper nasal section and a lower oral section, a malleable wire frame embedded in the material of said nasal section and being of a material which may be bent to fit the contour of a wearer's nose and reinforcing the mask in said nasal section and comprising a wire-like endless loop having one portion following the upper contour near the edge and a lower part joining the upper part to form apexes therewith adjacent the extremities of the upper part and extended across the mask, a second malleable wire frame embedded in the material of said mask in the oral section and bendable to fit the contour of a wearer's chin and reinforcing the chin section and comprising a wire-like endless loop having one portion following the lower contour near the edge and an upper part forming apexes with said lower part at the ends of the lower part and extended across the mask, the mask intermediate said sections being flexible to permit independent movement of said sections, and securing means for said mask including members disposed in the mask at said apexes and arranged to have head straps secured thereto.

7. A mask for the administration of a gas comprising a face portion formed to provide a chamber the walls of which are of soft, pliable material, the periphery of said mask being formed with a thin flexible face engaging portion of material breadth, the inner edge of said flange defining an opening for free access with said oral and nasal passages and being curved transversely to provide a convex zone for engagement with the face adapted to conform to the face due to the difference in pressure between the interior and exterior, said chamber providing an upper nasal section and a lower oral section, a malleable wire frame embedded in the material of said nasal section and being of a material which may be bent to fit the contour of a wearer's nose and reinforcing the mask in said nasal section and comprising a wire-like endless loop having one portion following the upper contour near the edge and a lower part joining the upper part adjacent the extremities of the upper part and extending across the mask, a second malleable wire frame embedded in the material of said mask in the oral section and bendable to fit the contour of a wearer's chin and reinforcing the chin section and comprising a wire-like endless loop having one portion following the lower contour near the edge and an upper part engaging said lower part at the ends of the lower part and extended across the mask, the mask intermediate said sections being flexible to permit independent movement of said sections and securing means for said mask including members disposed in the material at the mask close to and opposite to the joining parts of said frames and arranged to have head straps secured thereto.

8. A mask for the administration of a gas having a face piece formed of soft, pliable material, said face piece having a nasal section and an oral section, a malleable wire frame embedded in said material at said nasal section to stiffen said face piece, said frame being a wire-like loop

5 of material disposed in the upper part of the mask having one portion following the upper contour of the mask near the edge and the lower portion extending across the mask, said portions of the loop being bendable in different zones to conform to facial configurations of the wearer, said face piece being formed to provide a turret opening on each side of said oral section, check valves disposed in said openings to allow inhalation and exhalation of gaseous fluids, deflection means for at least one of said openings comprising an integral shield extending over and covering at least an upper portion of said check valve.

9. A mask for the administration of a gas having a face piece formed of soft, pliable material, said face piece having a nasal section and an oral section, a malleable wide frame embedded in said material at said nasal section to stiffen said face piece, said frame being a wire-like loop of material disposed in the upper part of the mask having one portion following the upper contour of the mask near the edge and the lower portion extending across the mask, said portions of the loop being bendable in different zones to conform to facial configurations of the wearer, said face piece being formed to provide a turret opening on each side of said oral section, check valves disposed in said openings to allow inhalation and exhalation of gaseous fluids, deflection means for at least one of said openings comprising an integral shield extending over and covering at least the upper half of said check valve said deflection means being flexible and in spaced relation to said valve.

10. A mask for the administration of a gas having a face piece formed of soft, pliable material, said face piece having a nasal section and an oral section, a malleable wire frame embedded in said material at said nasal section to stiffen said face piece, said frame being a wire-like loop of material disposed in the upper part of the mask having one portion following the upper contour of the mask near the edge and the lower portion extending across the mask, said portions of the loop being bendable in different zones to conform to facial configurations of the wearer, said face piece being formed to provide a turret opening on each side of said oral section, check valves disposed in said openings to allow inhalation and exhalation of gaseous fluids, deflection means for at least one of said openings comprising an integral shield extending over and covering at least the upper half of said check valve said deflection means being flexible and in spaced relation to said valve.

11. A mask for the administration of a gas comprising a face portion formed of soft, pliable material providing an upper nasal section and a lower oral section, a malleable wire frame comprising an endless wire loop embedded wholly within the material of said mask in a predetermined position and being of a material which may be bent to fit the contours of certain parts of the wearer's face and reinforcing the mask in said predetermined portion, said frame being in the nasal section and bendable to fit the contours of the wearer's nose.

12. A mask for the administration of a gas comprising a face portion formed of soft, pliable material providing an upper nasal section and a lower oral section, a malleable wire frame comprising an endless wire loop embedded wholly within the material of said mask in a predetermined position and being of a material which may be bent to fit the contours of certain parts of the wearer's face and reinforcing the mask in said predetermined position, said frame being in the oral section and bendable to fit the wearer's chin.

13. A mask for the administration of oxygen or other gas including a generally concavo-convex portion of flexible impervious material for covering the oral and nasal passages and having stiffening means embedded wholly within the material for holding the same away from the

face of a wearer, the periphery of said mask being formed with an inwardly extending face engaging portion comprising a thin highly flexible wide flange, the inner extremity of said flange defining an opening for free access with said oral and nasal passages, said flange being curved transversely to provide a convex zone portion for engagement with the face and having a wide face contacting portion adapted to engage and conform with irregularities of the face, the thinness of the flange being such that the difference in gas pressure between the interior and exterior holds the flange against the face and permits it to conform to the face without sliding upon movement of the mask relative to the face, said stiffening means being a malleable wire frame in the oral section and bendable to fit the contours of the wearer's chin and reinforcing the chin section.

14. A mask for the administration of a gas having a face piece formed of soft, pliable material, said face piece having a nasal section and an oral section, a malleable wire frame embedded in said material at said nasal section to stiffen said face piece, said frame being a wire-like loop of material disposed in the upper part of the mask having one portion following the upper contour of the mask near the edge, and the lower portion extending across the mask, said portions being bendable in different zones to conform to facial configurations of the wearer, said face piece being formed to provide a turret

15

5 opening on at least one side of said oral section, and a check valve disposed in said openings to allow exhalation, said valve thereby stiffening said oral section, and inlet means at said oral section to provide for the ingress of gas into said face piece.

10 15. A mask for the administration of a gas comprising

a face portion of soft, pliable material providing a nasal

and an oral section, stiffening means comprising at least

one endless malleable wire loop embedded wholly within

10 the material of said mask, said stiffening means being

positioned in the oral and nasal sections reinforcing the

mask in such sections and being bendable to conform to

configurations of the wearer's nose and chin.
